(57) **CLAIM**

The ornamental design for a portable electronic device, as shown and described.

DESCRIPTION

FIG. 1 is an isometric view of a portable electronic device according to a first embodiment;

FIG. 2 is a front view of the portable electronic device in FIG. 1;

FIG. 3 is a left side view of the portable electronic device in FIG. 1;

FIG. 4 is a right side view of the portable electronic device in FIG. 1;

FIG. 5 is a back view of the portable electronic device in FIG. 1;

FIG. 6 is a top view of the portable electronic device in FIG. 1;

FIG. 7 is a bottom view of the portable electronic device in FIG. 1;

FIG. 8 is an isometric view of a portable electronic device according to a second embodiment;

FIG. 9 is a front view of the portable electronic device in FIG. 8;

FIG. 10 is a left side view of the portable electronic device in FIG. 8;

FIG. 11 is a right side view of the portable electronic device in FIG. 8;

FIG. 12 is a back view of the portable electronic device in FIG. 8; and,

FIG. 13 is a top view of the portable electronic device in FIG. 8.

The broken lines shown in FIGS. 8-13 depict environment only and form no part of the claimed design.
